UNITED STATES PATENT OFFICE.

JOHN HADFIELD, OF AKRON, OHIO, ASSIGNOR TO THE HADFIELD RUBBER COMPANY,
OF AKRON, OHIO, A CORPORATION OF OHIO.

GLOVE.

1,097,018.

Specification of Letters Patent.

Patented May 19, 1914.

Application filed June 13, 1912. Serial No. 703,536.

To all whom it may concern:

Be it known that I, JOHN HADFIELD, a citizen of the United States, residing at Akron, in the county of Summit and State 5 of Ohio, have invented new and useful Improvements in Gloves, of which the following is a specification.

This invention relates to improvements in gloves, especially rubber gloves, and the object thereof is, broadly speaking, to provide a glove so constructed that ready flexion of the fingers and thumb of the user is possible without restraint or tension being imposed by the stretching of the gloves when bending or flexing the fingers.

Briefly, gloves, especially rubber gloves manufactured for physicians and surgeons use are constructed upon forms with the fingers of the form extended, and obviously, 20 the glove produced thereon is an exact replica of this form and hence, the gloves themselves are provided with normally-extended finger-portions. As these gloves are usually made, especially in the case of physicians and surgeons gloves, so as to fit the hand approximately snugly, to constitute a reasonably perfect fit for the hand of the wearer when the fingers are extended, but when the fingers are flexed or bent inwardly 25 to grasp an object, such as a surgical instrument, the upper portions of the glove across the back of the hand and over the backs of the fingers are stretched and drawn taut, requiring an effort on the part of the user 30 or wearer to flex his fingers, thereby stretching the portions of the gloves which cover the balls of the fingers sufficiently to put a tension on those portions, thereby straining the hand and dulling the sense of touch of 35 the finger tips which reduces the freedom of movement and sensitiveness of the hand covered by the ordinary glove to a considerable degree.

In view of the foregoing, it is a primary 40 object of this invention to provide a glove normally constructed with the fingers in the ordinary extended position with the portions of the glove which covers the fingers provided at or opposite the joints of the 45 hand and fingers on which the glove is to be used with bulged or outwardly-projecting portions which lie opposite but out of contact with the opposing portions of the hand to provide a certain amount of slackness at those points adjacent to the fingers

and joints to permit the ready movement of the fingers and thumb without imposing such a stress or tension on them as to impair their sensitiveness.

With the foregoing and other objects in view, the invention consists in the novel construction, combination, and arrangement of parts constituting the invention to be hereinafter specifically described and illustrated in the accompanying drawing which forms 60 a part hereof wherein is shown the preferred embodiment of the invention, but it is to be understood that changes, variations and modifications can be resorted to which come within the scope of the claim hereto 65 appended.

The drawing presented is a perspective view of a glove embodying this invention.

Referring to the drawing in detail, the reference numeral 1 denotes the glove preferably of rubber and preferably produced by what is known as the "dipping process," although it is obvious that gloves constructed of other material and by other methods than by the dipping method are entirely 75 within the scope of this invention. The glove will be customarily provided with projections at the points which normally cover the knuckles 2 and joints 3 of the human hand, so that there will be in the finished 80 product an excess of material at these points forming permanently outwardly-bulged portions designated in the drawing by the reference numeral 4. These outwardly-bulged portions will be of a size to permit free 85 flexion of the fingers when the fingers are bent to grasp an object such, for instance, 90 as a surgical instrument.

It will be obvious that the glove is best 95 constructed on a form having the finger portions extended as shown in the drawing, and with the bulges lying opposite to, but out of contact with those portions of the hands where the joints and knuckles are located and, of course, this refers equally well 100 to the thumb portion of the glove.

It will be obvious that when a glove constructed in accordance with this invention is withdrawn from the form it will have a permanently set form and the excessive material 105 which provides the bulged portions 4 will remain equally permanent, so much so that when used on the hand, it may be bent freely without stretching the finger portions, thereby enabling the fingers to be flexed or bent 110

at will without stretching the covering of the balls of the fingers, with the result that the material over the balls of the fingers is not strained sufficiently to decrease the sensitivity of the fingers, thereby largely enhancing the value of the glove in use especially in delicate surgical operations where sensitiveness is greatly needed.

5 I claim:
10 A seamless rubber glove of substantially

uniform thickness having over the knuckles bulged portions adapted to eliminate stress about the knuckles when the hand is closed.

In testimony whereof I have hereunto set my hand in presence of two subscribing witnesses.

JOHN HADFIELD.
